PISTON

Ralph R. Teeter, Hagerstown, Ind., assignor to
The Perfect Circle Company, Hagerstown,
Ind., a corporation of Indiana

Application July 31, 1934, Serial No. 737,891

2 Claims. (CL 309—13)

This invention relates to pistons for internal combustion engines and the like.

The principal object of my invention is to provide a piston so constructed that the desired clearances between the bearing faces of the skirt and the cylinder wall may be maintained throughout the operating range of the engine. More particularly I provide a piston of aluminum alloy or the like which has the skirt connected to the head by flexible struts and which is provided with simple and cheap means which causes the above mentioned desired clearances to be maintained and also overcomes other objectionable defects present in aluminum pistons of the slotted skirt type now on the market.

The above and further objects of my invention will appear more fully from the following description, reference being had to the accompanying drawing in which:

Fig. 1 is a vertical sectional view through the piston embodying the preferred form of my invention;

Fig. 2 is a vertical sectional view through the piston, the section being taken at 90° to that of Fig. 1;

Fig. 3 is a cross sectional view through the piston taken on the line 3—3 of Fig. 1;

Figs. 4 and 5 are top plan and side elevational views respectively, of the upper cross strut of the skirt; and

Fig. 6 is a side elevational view of one of the lower cross struts of the skirt.

The head 8 of the piston is connected to the inner ends of the piston pin bosses 9 by parallel flexible webs or hangers 10. The skirt 7 is separated from the head by the continuous slot 11 and the bosses 9 project inwardly from the skirt and are further connected to the skirt by the integral strengthening webs 8*.

The opposite sides of the upper portion of the skirt are connected together by a cross strut 12 which extends at right angles to the axis of the bosses 9 and between the hangers 10. This strut 12 is formed of metal such as Invar or steel, having a lesser coefficient of expansion than the aluminum alloy. In the preferred form shown, the strut 12 is channel-shaped in cross section and has elongated slots 29 in its upper face and at its ends it has folded portions 14 and pressed-in portions 15. As shown in Fig. 2 the folded portions 14 are embedded in thickened portions 16 of the skirt as are the ends of the sides of the channel, and the pressed-in portions 15 rest against the inner sides of the enlarged portions 16.

The opposite sides of the lower portion of the skirt are connected together by two parallel struts 17 which are similar in structure to the strut 12. The struts 17 have their ends embedded in thickened portions 18 of the skirt in substantially the same way as the end portions of the strut 12 are embedded in the portions 16 of the skirt.

In casting the piston, the inflexible struts 12 and 17 are placed in position in the mold and then the aluminum alloy is poured into the mold. As the alloy cools, it shrinks or contracts. The head shrinks more or less uniformly so that it retains its round or cylindrical form though its diameter is reduced. The struts 12 and 17, however, prevent any substantial reduction of the diameter of the skirt at right angles to the pin bosses, so that as the skirt cools the portions of the skirt in line with the bosses are drawn in and the skirt becomes elliptical with the bearing faces, midway between the bosses, lying on the major axis. It is obvious that the shrinkage of the aluminum alloy places the struts 12 and 17, which are inflexible, under constant compression. When the piston is cold, the skirt is sized or finished, as by form turning or grinding, the elliptical form being retained with the bearing faces lying on the major axis.

With the piston in the cylinder of a cold engine, there is the correct clearance between the bearing faces of the skirt and the cylinder wall throughout the length of the skirt. As the engine becomes heated in operation, the head expands twice as much as the skirt or thereabouts, as the head becomes much hotter than the skirt. As the head expands the distance between the hangers 10 tends to increase but this action does not materially affect the shape of the skirt as the hangers are quite thin and they flex to accommodate for the most part the difference between the expansion of the head and skirt due to the difference in temperatures. The skirt, however, tends to expand circumferentially due to the increase in its temperature. The struts 12 and 17 being under constant compression (with the bearing faces or portions of the skirt bearing against their ends and tending to move toward each other) the expansion of the aluminum alloy causes the diameter of the skirt at right angles to the bearing faces to increase. That is to say, the expansion for the most part takes place on the minor axis of the skirt. Or, in still other words, the expansion of the aluminum of the skirt tends to change the skirt from its elliptical form to one approaching a round form by increasing the length of the minor axis so that it approaches the

length of the major axis. The length of the latter axis may also slightly increase, due to the slight linear expansion of the struts and the slight increase in thickness in the aluminum of the skirt 5 at the end of the struts.

It will thus be seen that the diameter of the piston skirt from top to bottom is properly controlled during the operating range of the engine so that the desired clearance between the bearing 10 faces and cylinder wall is maintained throughout their length, the diameter of the skirt in line with the pin bosses being permitted to change without impairing the efficiency of the engine and without danger of scoring and the like.

15 It is understood that my invention is not limited to the details of construction shown and that other forms may be used without departing from the scope of my invention.

I claim:

20 1. A piston comprising a head, flexible hangers depending from said head and carrying pin bosses apertured to receive a piston pin, and a skirt integrally connected to said pin bosses, all formed of a metal having a high coefficient of expansion; 25 said head and skirt being axially spaced from each other throughout their entire circumference by a circumferentially extending air-gap and being maintained in such relation by said flexible hangers, said hangers being spaced inwardly from said skirt, the entire exterior surface of said skirt being generally elliptical in contour with the minor axis thereof substantially parallel to the axis of said pin bosses and the continuity of

said skirt being interrupted only by the pin boss apertures, and a pair of rigid struts having a lower coefficient of expansion than that of the metal of said skirt disposed below and spaced from said pin bosses, the ends of said struts being 5 embedded in the metal of said skirt.

2. A piston comprising a head, flexible hangers depending from said head and carrying pin bosses apertured to receive a piston pin, and a skirt integrally connected to said pin bosses, all formed 10 of a metal having a high coefficient of expansion; said head and skirt being axially spaced from each other substantially throughout their entire circumference by a circumferentially extending slot and being maintained in such relation by said flexible hangers, said hangers being spaced inwardly from said skirt, the entire exterior surfaces of said skirt being generally elliptical in contour with the minor axis thereof substantially parallel to the axis of said pin bosses 20 and the skirt having circumferential continuity save for the piston pin apertures; rigid strut means having a lower coefficient of expansion than that of the metal of said skirt, said strut means being disposed at right angles to said minor axis and below and spaced from said pin bosses; and further rigid strut means having a lower coefficient of expansion than that of the metal of said skirt disposed at right angles to said minor axis and above and spaced from said 25 piston pin bosses, the ends of all of said strut means being imbedded in the metal of said skirt.

RALPH R. TETTOR.
